Patented July 17, 1917.

2 SHEETS—SHEET 2.

UNITED STATES PATENT OFFICE.

RUBÉN RIVERA, OF SONSONATE, SALVADOR.

HYDRAULIC MOTOR.

1,233,913.

Specification of Letters Patent. Patented July 17, 1917.

Application filed May 20, 1916. Serial No. 98,718.

To all whom it may concern:

Be it known that I, RUBÉN RIVERA, a citizen of the Republic of Salvador, and a resident of Sonsonate, in the Republic of 5 Salvador, Central America, have invented a certain new and useful Improvement in Hydraulic Motors, of which the following is a specification.

My invention relates to improvements in 10 hydraulic motors, and it consists in the combinations, constructions, and arrangements of parts herein described and claimed.

The object of my invention is to provide 15 a hydraulic motor which is simple in construction, but which is highly efficient owing to a novel arrangement of the valve mechanism in which the shifting of the valves to turn the motive fluid first in one direction and then in the other is accomplished automatically and instantaneously.

A further object of my invention is to provide a valve shifting means in which a weight is actuated in such a manner that by its momentum the valve is given a quick 25 throw.

Other objects and advantages will appear in the following specification, and the novel features of the invention will be particularly pointed out in the appended claims.

30 My invention is illustrated in the accompanying drawings forming a part of this application, in which—

Figure 1 is a side elevation of the device, the cylinder and valve chest being shown in 35 section.

Fig. 2 is a view similar to Fig. 1 showing the parts in a different position.

Fig. 3 is a plan view.

40 Fig. 4 is an enlarged detail side view, certain of the parts being shown in section.

Fig. 5 is a section along the line 5—5 of Fig. 4.

Fig. 6 is a section along the line 6—6 of Fig. 4.

45 Fig. 7 is a section along the line 7—7 of Fig. 4, and

Fig. 8 is a section along the line 8—8 of Fig. 4.

In carrying out my invention I have provided a base 1 upon which is mounted a frame 2 which bears a cylinder 3 and a valve chest 4. Between the cylinder and the valve chest are the passages 5 and 6. An exhaust passage is shown at 7.

55 Disposed within the cylinder 3 is a piston 8 having a piston rod 9 which extends

through one end of the cylinder. This rod 9 is secured to a cross head 10 which is provided with a slot 11 running longitudinally of the head. Disposed in the slot are two 60 adjustable stop members 12 and 13 respectively. These stop members are provided with set screws 14 by means of which the position of one stop member with respect to the other can be adjusted. The stop members are provided with rollers 12^x and 13^x respectively.

At the opposite end of the cross head 10 from the piston rod 9 is a pitman 15 which is connected to a gear 16. The latter is on 70 a shaft 17 and is arranged to mesh with a pinion 18 on a shaft 19 which bears a drive pulley 20 at one end and a fly wheel 21 at the other. The shaft 19 is supported at the top by an upright 22.

75 Disposed between the uprights 2 and 22 is a support 23 at whose upper end is pivotally mounted a rod 24. The lower end of this rod is pivotally connected at 25 with an arm 26 which extends through a slot 27 in a guide plate 28, the latter bearing two stop members 29. The arm 26 is provided with a collar 30 at one end, and with a slideable bearing plate 31 which rests on the top of the guide member 28. A spring 32 surrounds the arm 26 and bears at one end upon the collar 30, and at the other end upon the bearing plate 31, the bearing surface of the latter being curved or convex, as shown in the drawings.

90 As will be seen from the drawings, the rod 24 passes through the slot 11 in the cross head 10. The rod is provided above its fulcrum 33 with a weight 34 which may be adjusted to the desired position along the rod 95 24. As will be seen from Figs. 1 and 2, the valve chest 4 has a slide valve 35 which is operated by means of a valve stem 36. The latter is connected to a block 37 which is provided with a slot 38 through which the rod 100 24 extends. The opposite end of the block 37 has connected to it a rod 39 which extends through a guide lug 40 on the upright 22 and which is provided with a nut 41 at its end for limiting the movement of the valve 105 stem.

From the foregoing description of the various parts of the device, the operation thereof may be readily understood.

Water or other suitable motive fluid is 110 admitted through a pipe 42 by opening a valve 43. In the position shown in Fig. 1

- the fluid will pass into the passage 5 and thence into one end of the cylinder 3 and will force the piston 8 toward the right in Fig. 1. The movement of the cross head 10 will cause the roller 12* of the stop member 12 to force the rod 24 to the right. This will tend to compress the spring 32. When the rod 24 passes its central position, that is to say the position in which the arm 26 and the rod 24 are in alinement, the lower end of the rod will be suddenly thrown to the left, due to the expansion of the spring 32. This will cause a sudden shifting of the valve 35 from the position shown in Fig. 1 to that shown in Fig. 2. The motive fluid will now enter the cylinder through the passage 6, thus causing the moving of the piston from the right to the left in Fig. 2, and causing the discharge of the motive fluid through the exhaust 7. The movement of the piston rod 9 toward the left in Fig. 2 will gradually force the rod 24 into a position in which the arm 26 and the rod 24 will be in alinement, when further movement will be caused by the sudden expansion of the spring 32 and the engagement of the lower end of the rod 24 with the block 37, thereby causing the shifting of the valve 35 to its original position.
- 30 The instantaneous shifting of the valve is due in a large part to the momentum of the weight 34 which is adjustable along the rod 24. The power delivered by the pitman 15 is transmitted by the crank gear 16 to the shaft 19 through the medium of the gear or pinion 18, and may be used for any suitable purpose.
- 40 The throw of the valve 35, as stated, may be limited in one direction by the position of the nut 41, and in the other direction by stop 36*, on the end of the valve 35. It will also be noted that the arm 26 rocks on the bearing 31 and that the lower end of the arm 26 has its movement limited by the stop members 29.

45 What I claim is:

1. In a hydraulic motor, a cylinder, a piston therein, a valve chest having communication with said cylinder, a valve disposed within the valve chest, a transmission mechanism connected with said piston for transmitting power from the latter, a valve stem, a spring-pressed valve-stem operating device, a pivoted rod, means carried by said piston for engaging said pivoted rod to swing it on its pivots, a spring for opposing the movement of the rod until the latter has reached a given position and for thereafter assisting the movement of the rod,
- 50 means carried by said valve stem for transmitting the movement of the rod to said valve stem for operating the latter, said last mentioned means comprising a slotted block carried by said valve stem and arranged to straddle said pivoted rod,
- 55 and arranged to straddle said pivoted rod,
- 60
- 65

said rod engaging said block at the ends of the slots, and a weight carried by said pivoted rod on the opposite side of the fulcrum from the spring.

2. In a hydraulic motor, a cylinder, a piston therein, a valve chest having communication with said cylinder, a valve disposed within the valve chest, a transmission mechanism connected with said piston for transmitting power from the latter, a valve stem, a spring-pressed valve-stem operating device, a pivoted rod, means carried by said piston for engaging said pivoted rod to swing it on its pivots, a spring for opposing the movement of the rod until the latter has reached a given position and for thereafter assisting the movement of the rod, means carried by said valve stem for transmitting the movement of the rod to said valve stem for operating the latter, said last mentioned means comprising a slotted block carried by said valve stem and arranged to straddle said pivoted rod, said rod engaging said block at the ends of the slots, and a weight carried by said pivoted rod on the opposite side of the fulcrum from the spring, said weight being adjustable along the rod.

3. The combination with a cylinder and a valve chest communicating therewith, of a piston in said cylinder, a slide valve in said valve chest, a piston rod, a slotted cross head secured to said piston rod, movable stop members in said slotted cross head, a pivoted rod having one end extending through said slotted cross head and adapted to engage said stop members, a slotted block, a valve stem connecting the said valve with said slotted block, the opposite end of said pivoted rod extending through said slotted block, and a spring connected with the end of the rod adjacent to said slotted block, the opposite end of the spring having a bearing member in alinement with the pivotal point of said rod.

4. The combination with a cylinder having a piston and a piston rod, of a valve chest having a valve and a valve stem, a slotted cross head secured to said piston rod, a slotted block secured to said valve stem, a support, a rod pivotally mounted on said support, one end of said rod extending through said slotted cross head, and the opposite end extending through said slotted block, an arm pivotally connected to last mentioned end, a spiral spring carried by said arm, a guide member having a slot arranged to receive said arm and being provided with a bearing surface, a bearing member disposed on said arm, one end of said spiral spring bearing against said arm and the other against said bearing member.

5. The combination with a cylinder having a piston and a piston rod, of a valve chest having a valve and a valve stem, a

slotted cross head secured to said piston rod, a slotted block secured to said valve stem, a support, a rod pivotally mounted on said support, one end of said rod extending 5 through said slotted cross head, and the opposite end extending through said slotted block, an arm pivotally connected to last mentioned end, a spiral spring carried by said arm, a guide member having a slot arranged to receive said arm and being provided with a bearing surface, a bearing member disposed on said arm, one end of said spiral spring bearing against said arm and the other against said bearing member, and stop members carried by said slotted guide member for limiting the movement of said spring bearing arm.

RUBÉN RIVERA.
